DESIGN FOR A BACK WALL FOR GAS HEATERS

Hubert R. Humphrey, Kalamazoo, Mich., assignor
to General Gas Light Company, Kalamazoo,
Mich.

Application November 12, 1934, Serial No. 53,985

Term of patent 7 years

To all whom it may concern:

Be it known that I, Hubert R. Humphrey, a citizen of the United States, residing in the city and county of Kalamazoo, State of Michigan, have invented a new, original, and ornamental Design for Back Wall for Gas Heaters, of which the following is a specification, reference being had to the accompanying drawing, forming part thereof, in which:

Fig. 1 is a front elevation,
Fig. 2 is an end elevation, and
Fig. 3 is a fragmentary horizontal section of a back wall for gas heaters on lines 3—3 of Figs. 1 and 2, embodying my new design.

I claim:

The ornamental design for a back wall for gas heaters, as shown.
